UNITED STATES PATENT OFFICE.

JOSEPH KINTZ, OF BALLARD VALE, MASSACHUSETTS, ASSIGNOR TO HIMSELF AND THE CRAIGHEAD & KINTZ MANUFACTURING COMPANY, OF MASSACHUSETTS.

SUSPENSION-LAMP.

SPECIFICATION forming part of Letters Patent No. 400,856, dated April 2, 1889.

Application filed October 4, 1888. Serial No. 287,206. (No model.)

To all whom it may concern:

Be it known that I, JOSEPH KINTZ, of Ballard Vale, in the county of Essex and State of Massachusetts, a citizen of the United States, 5 have invented certain new and useful Improvements in Suspension-Lamps, of which the following is a specification.

My invention relates to that class of suspension-lamps in which a spring-actuated 10 winding-drum is employed to take up and release the suspension-chains by which the lamp-fixture is hung from the ceiling, this drum having its motion controlled by a spring-latch having a connection extending to the 15 lower portion of the fixture, by which the latch may be opened when it is desired to raise or lower the lamp.

In the accompanying drawings I have represented at Figure 1, in vertical section, a 20 suspension-lamp embodying my present improvement, and at Fig. 2 an enlarged view of details of the apparatus, as will be herein-after more fully explained.

The drawings show a fixture comprising the 25 raising and lowering drum A, supporting-chains B B, winding and unwinding from said drum, supports C C, preferably chain, extending from the drum-case downwardly to the shade-ring D, pendent from which are brackets 30 supporting the lamp-fount-cup support E; also, I have shown in connection with the drum a latch, F, mounted upon a spring, G, within the drum-case, and provided with an extension, H, passing downwardly through the 35 drum-case. All the parts thus far described are substantially such as have been heretofore employed in lamps of this character.

The immediate object of my present invention is to so construct and arrange the connection whereby the spring-latch F may 40 readily be operated from the lower part of the fixture, when it is desired to raise or lower it, that the same shall be both graceful in appearance, simple in construction, and easy in 45 operation. I accomplish these results by means of the following mechanism: Attached to the lower end of the extension H is a bent rod or cross-bar, I. From the extremities of this cross-bar I chains K K descend, and their 50 lower extremities are connected with the upper ends of the arms of a stirrup, L, adapted

to conform substantially in its shape to the outline of the lamp-fount-cup support and to move vertically within the same. To the 55 lower part of this stirrup is attached a downward connection, M, terminating in a suitable finger-grasp—as, for example, the ring N.

With the construction above described a 60 neat, simple, and convenient device is afforded for operating the spring-latch from the lower part of the fixture.

It will be understood that the tension of the spring G, which normally holds up the latch F in engagement with the drum, also 65 causes the stirrup L to be lifted or held up by reason of the connection through the chains and cross-bar. When now it is desired to withdraw the latch, in order to permit the drum to revolve, to raise or lower the fixture, this may be done by pressing down the ring N, and so long as this is held downward 70 the fixture may be raised or lowered. (See Fig. 2.) When the pressure upon the ring N is released, the latch F is free to move upward, 75 under the tension of the spring G, to engage with the drum and stop its revolution, thereby holding the fixture in suspension.

The location of the stirrup L within the lamp-fount-cup support is a desirable feature, 80 because this stirrup is necessarily of fragile construction, and being within the lamp-fount-cup support, is thereby protected from accidental injury by a blow or otherwise. Furthermore, the passages or holes in the upper portion of the lamp-fount-cup support, 85 through which the arms of the stirrup move, serve to center it and prevent it from turning, and thus, the lamp-fount-cup support itself being utilized for this purpose, no additional guides for the stirrup need be provided.

I am aware of the structures described and shown in United States Letters Patent No. 285,381, dated September 26, 1883, and No. 311,224, dated January 27, 1885, and disclaim 95 as of my invention anything therein shown or described.

I claim—

In a suspension-lamp of the character described, the combination, with the mechanism 100 which controls the motion of the raising and lowering drum, of a hollow lamp-fount-cup support, E, a stirrup, L, located and vertically

movable therein and having its upper portions passing through the upper portion of the lamp-fount-cup support, a finger-grasp, N, attached to the lower part of the stirrup, and 5 connections K, extending upwardly from the upper ends of the said stirrup and attached to the extremities of a cross-bar, I, connected with the drum-controlling latch, all substantially as set forth.

In testimony whereof I have hereunto sub- 10
scribed my name this 25th day of September,
A. D. 1888.

JOSEPH KINTZ.
